UNITED STATES PATENT OFFICE.

EDWARD R. SARGENT, OF NEW HAVEN, CONNECTICUT, ASSIGNOR TO SARGENT & COMPANY, OF NEW HAVEN, CONNECTICUT, A CORPORATION OF CONNECTICUT.

CASKET-HANDLE.

1,301,176.

Specification of Letters Patent. Patented Apr. 22, 1919.

Application filed June 2, 1917. Serial No. 172,466.

To all whom it may concern:

Be it known that I, EDWARD R. SARGENT, a citizen of the United States, residing in the city and county of New Haven, State of Connecticut, have invented certain new and useful Improvements in Casket-Handles, of which the following is a full, clear, and exact description.

This invention relates to casket handles, and it has particular reference to those of the type wherein a handle bar is supported by arms pivoted to so-called socket plates. The invention also has special reference to handles of this type which are made wholly from sheet metal and which are of the cheaper grade.

One of the objects of the invention is to provide what I may term an "all steel" handle which is of very low cost.

Another object of the invention is to provide a composite construction of steel arm in which a thin flat plate of steel or similar metal, which is sufficiently strong to take up most of the lifting strain, has applied thereto a finishing plate, also preferably of steel, which can be stamped or otherwise ornamented in any suitable manner.

Another object of the invention is to provide improved means for pivoting the arm to the socket plate.

To these and other ends, the invention consists in the novel features and combinations of parts to be hereinafter described and claimed.

In the accompanying drawings,

Figure 1 is a front elevation of a casket handle embodying my improvements, showing part of the handle bar;

Fig. 2 is a side elevation;

Fig. 3 is a rear elevation of the parts shown in Fig. 1;

Fig. 4 is a section on line 4—4 of Fig. 3;

Fig. 5 is a section on line 5—5 of Fig. 3 with the arm in its lowermost position;

Fig. 6 is a view similar to Fig. 5, showing the arm in its raised position;

Fig. 7 is a detail of the main plate from which the arm is constructed;

Fig. 8 is a section on line 8—8 of Fig. 1;

Figs. 9, 9^A and 10 are details hereinafter described;

Figs. 11, 12 and 13 are a front elevation, a side elevation, and a section on line 13—13 of Fig. 11, respectively, of a modified handle construction.

55

The base or socket plate 20 is preferably made of sheet metal having rearwardly turned marginal portions to rest against the wall of the casket or box, and this plate is provided with the customary screw holes 21 at the lower part thereof through which the attaching screws (not shown) are passed.

At the lower middle part of the plate 20, the same is provided with an opening for the passage of the arm 22. This opening is in 60 the form of a T-shaped slot 23 (Figs. 9 and 9^A). The vertical part of the slot receives the main plate 24 of the arm 22 and the upper transverse part of the slot, which may be slightly curved as shown, receives the 65

finishing plate 25 of the arm, which finishing plate is applied to the edge of the main plate. The blank from which the main plate is made is shown in detail in Fig. 7. At one end of the plate the same is provided 70 with an opening 26, and extending into this opening is a lug 27 having a hole 28. The lug 27 is subsequently bent laterally, as shown in Fig. 3, and the hole 28, which is

screw threaded, receives a screw 29, which secures the handle bar 30 in place in the 75 opening 26, as shown in Fig. 2. At the upper end of the main plate 24, the same is provided with a head or enlargement 31 having a rearwardly directed integral lug 80

32. This lug 32 co-operates with a bridge piece 33 which extends over the T-shaped slot from top to bottom and is riveted to the rear face of the plate 20 above and below the slot by rivets 34, 35. The portion of the 85

bridge piece located back of the slot in the plate is curved rearwardly to present a semi-cylindrical socket into which the head 31 extends. The bridge piece is provided with a longitudinal median slot 36 in line with the 90

upright part of the T-shaped slot 23, and after the lug on the main arm plate 24 has been passed through the slot 36, it is bent over, as shown at 32^A in Fig. 3, so as to overlie the rear surface of the curved part of 95

the bridge piece at one side of the slot 36. In this manner, the arm is retained against 100

outward displacement in its socket and pivotal movement of the arm in the socket is provided for. The lug 32^a also limits the lifting movement of the arm, for when the 5 arm is lifted to the extent shown in Fig. 6 the lug abuts the lower part of the bridge piece adjacent the lower end of the slot 36 in said bridge piece, as shown. In this manner, the lifting strain is transmitted effectively to the bridge piece.

10 The finishing plate 25 of the arm may advantageously be applied to the edge of the main arm 24 by means of integral tenons or lugs 37, 38, 39 on the main arm plate which 15 extend through openings or slots in the finishing plate and are riveted therein. While the finishing plate is located transversely to the main plate, it is preferably arched in cross-section, as shown in Fig. 8, 20 and it will be observed from Fig. 8 that the side edges 39 of the lower part of the finishing plate which are located adjacent the handle bar 30 are brought flush with the inner edge of the opening or socket 26 in the 25 main arm plate so as to bear on the handle and thereby prevent it from canting. In this manner, a broad bearing of the arm on the bar over a considerable part of the circumference of the bar is provided.

30 The finishing plate preferably terminates at a point which is just beneath the bar when the arm is in the pendant position as shown in Fig. 2. This finishing plate may be stamped or otherwise ornamented in many 35 different ways, and different kinds of finishing plates may be used with the same type of main arm plate, as will be obvious. The finishing plate in this form of the invention extends on both sides of the main arm plate, 40 and as stated is formed as a separate part riveted to the edge of the main arm plate, the side edges of the finishing plate being bent down to engage the surface of a round bar received in a round opening in the lower 45 part of the main arm plate.

In the form shown in Figs. 11, 12 and 13, the construction is quite similar to that just described except that in this case the part 50 of the finishing plate 25^a which extends into proximity to the bar 30 is less arched in cross-section and its side edges do not engage the bar. Here the side edges are spaced from the bar as shown in Fig. 13, but an extended bearing surface on the bar is 55 provided by interrupting the main arm plate 24^a at 40 and bending the arms thus formed in opposite directions to present lugs 41 which extend longitudinally of the bar and bear thereon, as shown more particularly in 60 Fig. 11. In this way canting of the bar with respect to the arm is to a large extent prevented.

65 By the construction described a very cheap but efficient steel handle may be provided, the parts of which can readily be

made of sheet steel or other sheet metal by means of suitable dies.

Changes may be made in the details without departing from the scope of the invention as set forth in the claims.

I do not claim broadly herein a casket handle or the like, comprising a sheet metal socket plate having an opening, a supporting plate at the rear of said socket plate having a rearwardly curved portion, rivets 70 for connecting said supporting plate with said socket plate above and below said opening, and an arm having a portion passing through said opening, and provided with a retaining lug bent laterally to engage and 75 ride on the rear surface of the curved portion of said supporting plate, as claimed in my Patent No. 1,241,288, granted September 25, 1917.

What I claim is:

1. In a casket handle or the like, a socket plate having a slot extending therethrough, a slotted bridge piece secured to said socket plate at the rear thereof, and a sheet metal arm extending through the slots of the 90 socket plate and bridge piece and having a turned over retaining lug at the back of the bridge piece.

2. In a casket handle or the like, a sheet metal socket plate having a slot in the front 95 wall thereof, a supporting plate riveted to said socket plate above and below said slot, said supporting plate having a slot aligned with said first slot, and an arm having a thin flat web extending through said slots 100 and provided with a laterally bent lug engaging the rear surface of said supporting plate.

3. In a casket handle or the like, a sheet metal socket plate having a T-shaped slot, 105 a sheet metal arm of T-shaped cross-section engaging said slot, and means at the rear of the plate for pivoting the arm to the plate.

4. In a casket handle or the like, a sheet metal socket plate having an elongated vertical slot with a lateral extension at the upper part thereof, a flat sheet metal arm member extending through the vertical part of said slot and having a lateral extension at the front part thereof engaging the 115 lateral portion of said slot, and means at the rear of said socket plate for pivoting said arm member thereto.

5. In a casket handle or the like, a socket plate having an elongated vertical slot with 120 a lateral extension at the upper part thereof, a flat sheet metal arm member extending through the vertical part of said slot and having a lateral extension at the front part thereof engaging the lateral portion of said 125 slot, and means at the rear of said socket plate for pivoting said arm member thereto, said pivoting means comprising a slotted plate applied at the rear of the socket plate through which said arm member passes and 130

a retaining lug on said arm member engaging said slotted plate.

6. In a casket handle or the like, a base plate having a slot in the front wall thereof, 5 an arcuate plate having a slot therein mounted upon the rear face of said base plate, and a sheet metal arm extending

through said slots, said arm having a lug slidably engaging the convex surface of said arcuate plate, whereby said arm is pivotally 10 secured to said base plate.

In witness whereof, I have hereunto set my hand on the 1st day of June, 1917.

EDWARD R. SARGENT.
